UNITED STATES PATENT OFFICE.

WILLIAM McCONNELL, OF WASHINGTON, RHODE ISLAND.

WINDING-ON MECHANISM FOR SPINNING-MULES.

SPECIFICATION forming part of Letters Patent No. 286,460, dated October 9, 1883.

Application filed December 6, 1879.

To all whom it may concern:

Be it known that I, WILLIAM McCONNELL, of Washington village, in the county of Kent and State of Rhode Island, have invented certain new and useful Improvements in Winding-On Mechanism for Spinning-Mules, of which the following is a specification.

This invention relates to spinning-mules such as that shown in the patent to P. McGovern, No. 153,975, dated August 11, 1874, in which a quadrant-wheel is employed to effect the revolution of the spindles at a uniformly-diminishing rate as the cops increase in size to insure a uniform strain upon the yarn as it is being wound. In mules of this class the quadrant is provided with a screw-threaded shaft carrying a slide, and the quadrant-chain is connected to this slide and passes around and turns a drum or pulley that indirectly revolves the spindles. The said quadrant, and with it the screw-threaded shaft, has imparted to it a uniformly-oscillating motion, such motion being produced through suitable connecting mechanism by the movements of the carriage, and made to conform thereto. It is therefore obvious that, by varying upon this shaft the position of the slide to which the quadrant-chain is attached, a variation in the amount of travel of such slide as the quadrant oscillates will be produced, and consequently a corresponding variation in the number of revolutions of the drum and spindles which are indirectly revolved by said drum. Heretofore the upward movement of the slide has been produced by a weighted clutch attached to the carriage, which at each stretch drops upon and drags along with it as the carriage moves inward an endless cord, thus turning a wheel on the quadrant-axle, and indirectly, through intermediate cog-gear, turning the quadrant-shaft, which latter, being screw-threaded, forces the slide upward, this construction being shown in the patent to P. McGovern, No. 118,808, dated September 12, 1871; but in this mechanism the clutch is liable to slip. Besides, the ratio of decrease in the number of revolutions of the spindles at each succeeding stretch is normally constant and regular, whereas it

should vary, as is obvious in practice, so that there will be a uniform strain upon the yarn 50 as it is being wound.

The object of my invention is to produce a simple and efficient mechanism which will obviate these objections and have a positive and uniform action, as will be hereinafter more 55 fully described, and particularly pointed out in the claims.

In the drawings, Figure 1 is a perspective view of so much of a spinning-mule with my improved mechanism applied thereto as is necessary for an illustration of my invention. Fig. 2 is a side view thereof, and Fig. 3 is a top or plan view of the same.

Corresponding parts in the several figures are denoted by the same letters of reference. 65

Referring to the drawings, A designates the quadrant, and b is the screw-threaded shaft which is carried thereby, the latter being provided with a handle, d, at one end, and with a bevel-wheel, e', at its other end, which wheel 70 e' meshes with a corresponding bevel-wheel, e, that is arranged on the shaft C, on which the quadrant turns. c is the slide on screw-threaded shaft b, and i is the quadrant-chain, which is secured to the slide and passes around 75 a drum, m, as shown. t is a cord or band by which power is transmitted from the carriage (shown in dotted lines) to the quadrant through a gear-wheel, x, that meshes with the quadrant, as shown in the patent to McGovern, No. 80 153,975, above noted.

B is a track that is secured on the floor at right angles to the shaft of the quadrant, and in this track travels a rack, C, having an upright arm, D, as shown. By the outward movement of the carriage it presses against the arm D and causes the rack C to travel toward the quadrant. As the carriage recedes, the rack C is forced back by action of the spring E, that is connected with a horizontal shaft arranged 90 at right angles to the rack, that carries a gear-wheel, F, meshing with the rack C. It is obvious that as the rack is forced toward the quadrant it will wind up this spring E, which latter is fixed at one end, A⁵, to the side of 95 track B, which supports and guides the rack

C, and at the other end to the shaft B⁵ of the gear-wheel F.

On the shaft B⁵ is fixed a ratchet-wheel or disk, G, and loosely on the said shaft B⁵ is arranged a gear-wheel, H, having a disk, H⁸, fixed to its hub. This disk H⁸ carries a pivoted pawl, K, that is adapted to engage the fixed ratchet-disk G in such a manner that when the shaft B⁵ is revolved toward the quadrant by the movement of the slide C as it is actuated by the spring E, the teeth of the said ratchet-disk G will pass under the pawl K as the disk G is revolved toward the quadrant with its shaft B⁵, and the loosely-arranged gear-wheel H will not be turned; but when the shaft B⁵ is turned in the opposite direction on the return movement of the slide C, the disk G, as it moves with the shaft, will have its teeth locked in engagement with the pawl K, and the wheel H, which is connected, as above described, with said pawl, will be carried around with the shaft B⁵. The gear-wheel H is thus revolved in only one direction—i. e., from the quadrant—while the shaft B⁵ turns in both directions. Therefore, when the carriage moves outward toward the quadrant, and pushes the rack C along by its engagement of the arm D, the gear-wheel H will be turned, as before stated, and this movement of wheel H is transmitted through an intermediate gear-wheel, L, to a gear-wheel, M, fixed on the shaft C⁵, on which the quadrant turns. As the shaft C⁵ turns, it operates to raise the slide c by means of the bevel-wheels e and e', the former of which being attached to the shaft C⁵, and the latter to the screw-threaded shaft b. The gear-wheel H is thus intermittently at rest and in motion, its motion being only in the one direction, and when the carriage moves back the wheel H and all the mechanism operated thereby, including the slide c, remains stationary.

It is obvious that the disk H⁸ can be dispensed with, when the pawl K will be pivoted directly to the gear-wheel H, and the latter will be arranged closely to the fixed ratchet-disk G.

It is necessary, in order to maintain a uniform strain upon the yarn, that the slide c, which moves in a guide, D⁵, on the quadrant-arm, should be raised less and less at every succeeding stretch. Therefore its upward movements are decreased by decreasing the distance for the rack C to travel in the track B back and forth, as follows: To the slide c is attached a chain, S, which passes down and around a pulley, or between two pulleys, 1 and 2, as herein shown, and is secured at its other end to a wheel or drum, N, fixed on a shaft, E⁵, arranged at right angles to track B, and carrying another fixed wheel or drum, P, and also a cam, R. To the wheel P is attached a chain, T, which is also connected to a drag, W, that moves along in the track B. By means of this mechanism, as the slide c is raised, it

causes the drag W to move in track B, thereby shortening the distance for the rack C to travel back and forth. When the slide c is raised high enough, the shaft E⁵ will be around far enough to cause the cam R to bear on a lever, Z, to press it down out of a slot, F⁵, in a bolt, y, that is arranged parallel with the shaft E⁵. The released bolt y is then forced by a suitably-arranged spring, o, through a slot, G⁵, in the side of track B, and back of the rack C, to prevent the return of the latter, so that the mechanism operated by said rack C will be thrown out of operation. A lever, Q, is connected with the bolt y, and can be operated to return the said bolt back to its normal position against the tension of spring o.

The gear-wheel M upon the shaft C⁵, on which the quadrant turns, is to be changed according to the size of the yarn to be spun, for the thicker the yarn the more rapid the decrease should be in the rate of revolutions of the spindles; hence for spinning coarse yarn the gear-wheel M should be comparatively small, and large for fine yarn. Thus the rate of the upward movement of slide c is easily varied by varying the size of this wheel M.

U designates a lever that is fulcrumed on the end of shaft B⁵ and carries the gear-wheel L, the bearing-pin G⁶ of which is adjustable in a slot, H⁵, in the said lever, so that the position of the wheel L can be changed to correspond with the size of the wheel M. At the free end of this lever U is fulcrumed a latch-lever, I⁵, which engages a bracket, J⁵, to retain lever U down in position. When it becomes necessary to change wheel M, the latch-lever I⁵ can be disengaged from the bracket J⁵, to enable the lever U to be thrown over to the position shown in dotted lines, Fig. 2, of the drawings.

The operation and advantages of my invention will be readily understood and appreciated by those skilled in the art to which it appertains. It is simple and efficient, and is adapted for use in connection with mules other than those in the above-mentioned patents.

I claim as my invention—

1. The combination, with the quadrant of a mule spinning-machine, of shaft C⁵, gears e e', screw-shaft b, slide c, chain S, pulleys 1 and 2, wheels N and P, cam R, lever Z, bolt y, spring O, lever Q, chain T, drag W, track B, rack C, arm D, spring E, cog or gear wheel F, ratchet-wheel G, pawl K, disk H⁸ for supporting said pawl, and gear-wheels H, L, and M, as set forth.

2. The combination of the track B, rack C, arm D, spring E, gear-wheels F and H, shaft B⁵, ratchet-wheel G, pawl K, disk H⁸ for supporting said pawl, gear-wheel L, having a suitable support, gear-wheel M, the shaft E⁵, the quadrant and means for operating it, the intermediate shaft, C⁵, gears e e', quadrant-

screw *b*, slide *c*, and the carriage of the mule, all combined and operating substantially as and for the purpose set forth.

3. The combination of the quadrant, the quadrant screw-slide *c*, bevel-wheels *e* and *e'*, pulleys 1 and 2, chain *S*, and wheel *N*, as and for the purpose set forth.

4. The combination of the quadrant screw-slide *c*, the quadrant and means for operating

the same, chain *S*, pulleys 1 and 2, supports 10 therefor, wheels *N* and *P*, shaft *E*, chain *T*, drag *W*, and track *B*, as and for the purpose set forth.

WILLIAM McCONNELL. [L. S.]

In presence of—

JOHN P. WALKER,
F. HACKER.
